UNITED STATES PATENT OFFICE.

LOUIS B. PRAHAR, OF BROOKLYN, NEW YORK.

DESIGN FOR A BUCKLE.

SPECIFICATION forming part of Design No. 21,392, dated March 8, 1892.

Application filed February 3, 1892. Serial No. 420,231. Term of patent 3½ years.

To all whom it may concern:

Be it known that I, LOUIS B. PRAHAR, a citizen of the United States, residing at Brooklyn, in the county of Kings and State of New York, 5 have invented and produced a new and original Design for a Buckle, of which the following is a specification, reference being had to the accompanying drawing, forming part thereof, which represents a plan view of a buckle decorated in accordance with my design.

In general contour the buckle is rectangular, and its center is ornamented by a figure simulating the portrait of Columbus. An 15 open panel effect is produced at the sides and above and below the portrait figure, and the

upper and lower panel figures are apparently inclosed by leg-like scrolls. At the corners of the buckle bead-like figures are arranged in angular grouping, and between the side 20 margins and the side panel figures reversely-arranged semicircular scrolls are placed, while above and below the side panel figures a series of tendril-like figures are carelessly disposed. 25

I claim—

The design for a buckle, substantially as herein shown and described.

LOUIS B. PRAHAR.
